UNITED STATES PATENT OFFICE.

JULIUS C. LOWRY, OF DETROIT, MICHIGAN.

DESIGN FOR A LIGHTING FIXTURE.

Application filed January 26, 1929. Serial No. 29,785. Term of patent 7 years.

To all whom it may concern:

Be it known that I, JULIUS C. LOWRY, a citizen of the United States, residing at Detroit, in the county of Wayne and State of Michigan, have invented a new, original, and ornamental Design for a Lighting Fixture, of which the following is a specification, reference being had to the accompanying drawing, forming part thereof.

Fig. 1 is a plan view of a lighting fixture embodying my invention.

Fig. 2 is a front elevation thereof.

I claim:

The ornamental design for a lighting fixture as shown.

JULIUS C. LOWRY.
